[57] **CLAIM**

The ornamental design for an asymmetrically shaped bottle with a sloping shoulder, as shown and described.

DESCRIPTION

FIG. 1 is a front and left-side perspective view of a first

embodiment of an asymmetrically-shaped bottle with a sloping shoulder, showing my new design;

FIG. 2 is a rear elevational view thereof;

FIG. 3 is a front elevational view thereof;

FIG. 4 is a top plan view thereof;

FIG. 5 is a right side elevational view thereof;

FIG. 6 is a left side elevational view thereof;

FIG. 7 is a bottom plan view thereof;

FIG. 8 is a sectional view taken along line 8—8 of FIG. 2; and,

FIG. 9 is a sectional view taken along line 9—9 of FIG. 2;

FIG. 10 is a rear elevational view of a second embodiment of said bottle showing my new design;

FIG. 11 is a front elevational view thereof;

FIG. 12 is a right side elevational view thereof;

FIG. 13 is a top plan view thereof;

FIG. 14 is a sectional view thereof taken along line 14—14 of FIG. 10;

FIG. 15 is a sectional view thereof taken along line 15—15 of FIG. 10; and,

FIG. 16 is a left and side perspective view thereof, reduced in size.

The bottom of the second embodiment of the asymmetrically shaped bottle with sloping shoulder is flat and unornamented.
